United States Patent Office

Des. 215,336
Patented Sept. 23, 1969

215,336

BASE FOR A HIGH-INTENSITY LAMP

Warren C. Portman, Peekskill, and Alex J. Weinstein,
Croton-on-Hudson, N.Y., assignors to The Ednalite
Corporation, Peekskill, N.Y., a corporation of New
York

Filed Oct. 29, 1968, Ser. No. 14,212

Term of patent 14 years

Int. Cl. D26—02

U.S. Cl. D48—20

Fig. 2.

Fig. 3.

Fig. 4.

Fig. 5.

Fig. 6.

FIG. 1 is a perspective view showing the design of a lamp base according to this invention;

FIG. 2 is an enlarged side elevational view with the adjustable arms of the base being in positions other than those shown in FIG. 1, said arms being fragmentarily shown for purposes of disclosure;

FIG. 3 is a side elevational view similar to that of FIG. 2, but showing the adjustable arms in still another position;

FIG. 4 is a top plan view with the adjustable arms in the position of FIG. 2; and

FIGS. 5 and 6 are respectively front and back elevational views of the lamp base with the adjustable arms being fragmentarily shown for convenience of illustration.

We claim:

The ornamental design for a base for a high-intensity lamp, substantially as shown and described.
